[57] **CLAIM**

The ornamental design for a ceiling-mounted monitor system, as shown and described.

DESCRIPTION

FIG. 1 is an isometric view of a ceiling-mounted monitor system showing my new design, the monitor being depicted in its open orientation;

FIG. 2 is an isometric view of a ceiling-mounted monitor system showing my new design, the monitor being depicted in its closed orientation;

FIG. 3 is a bottom view of the ceiling-mounted monitor system as shown in FIG. 1;

FIG. 4 is a top view thereof;

FIG. 5 is a front view thereof;

FIG. 6 is a rear view thereof; and,

FIG. 7 is a left side view thereof, the right side view being a mirror image.
